H. EVERETT'S

DESIGN FOR AN OIL CAN.

Patented April 5, 1864.

U. S. Patent Office
Washington, D. C.

Henry Everett
Attest. H. Everett

DES. 1927

H. Everett, of Philadelphia, Penna.

Letters Patent No. 1927-Dated April 6th 1864.

Design for an Oil Can.

The schedule referred to in this Letters Patent and making part of the same,

are

Scull whom it may concern:

Be it known that G. H. Everett, of Philadelphia, County of Philadelphia, State of Pennsylvania, have invented, or produced a new and original design for an Oil Can, and I do hereby declare the accompanying drawing, with the following explanation of the same, to form a full, clear and exact description of the said design.

The figure in the annexed drawing represents my design for an Oil Can, in perspective.

The can consists of a hollow cylindrical case A, having a permanent ornamental cover plate B which is slightly convex, and which has a central opening surrounded by an annular projection a, the ornaments consisting of corrugations b, radiating from the annular projection a, as clearly illustrated in the drawing.

I claim: The shape and configuration, substantially as described, of the can, and its cover plate B.

In testimony whereof, I have signed my name to this specification in the presence of two subscribing witnesses:

Witnesses:

Henry Howson
John White.
